(57) **CLAIM**

The ornamental design for a planter as shown and described.

DESCRIPTION

FIG. 1 is a front and top perspective view of a planter;

FIG. 2 is a front perspective view thereof;

FIG. 3 is a top plan view thereof;

FIG. 4 is a left side perspective view thereof; and,

FIG. 5 is a bottom plan view thereof.

The dot-dash lines define the bounds of the claimed design and form no part thereof.
